[57] CLAIM

The ornamental design for a packaging container or similar article, substantially as shown.

DESCRIPTION

FIG. 1 is a perspective view of a packaging container or similar article showing my new design;

FIG. 2 is a top plan view thereof;

FIG. 3 is a front elevational view thereof;

FIG. 4 is an end elevational view thereof as viewed along lines 4—4 of FIG. 3;

FIG. 5 is an end elevational view thereof as viewed along lines 5—5 of FIG. 3;

FIG. 6 is a rear elevational view thereof as viewed along lines 6—6 of FIG. 4; and

FIG. 7 is a bottom plan view thereof as viewed along lines 7—7 of FIG. 6.
